WATER CONTROL FOR DISPOSAL UNITS

James H. Powers, Westport, Conn., assignor to
General Electric Company, a corporation of
New York

Application October 30, 1947, Serial No. 783,140

4 Claims. (Cl. 241—36)

1

My invention relates generally to waste disposal units, sometimes called garbage grinders. More particularly, my invention relates to the driving controls and associated parts for such disposal units. It is customary for these devices to be connected to a kitchen sink or other receptacle which has water supplied thereto. The water is used in the grinder to aid in the comminution of garbage or other waste, and to flush the ground material to the discharge pipe, which may lead to a conventional trap and sewer.

If insufficient water is supplied to the waste material, the grinding process is prolonged unnecessarily, and the ground waste may not be washed away from the grinder, thus clogging the mechanism.

One of the objects of the present invention is to simplify the controls for the drive of such a grinder. Installation of the unit can also be made more easily and, therefore, it will be less costly. Another object is to increase the safety factor in operation of these devices. Still another object is to insure a proper flow of flushing water to the grinder at all times when it may be operating, and to prevent operation of the grinder if sufficient water is supplied thereto.

These, and other objects, are obtained by locating a part of the control mechanism for the grinder drive upon a portion of the casing or housing for the grinder, for example, just above the grinder itself. This part of the control is responsive to the flow of water in the casing. Other parts of the drive control are also carried by the casing so that all plumbing and electrical connections need be made to the disposal unit only, and no connections need be made to any inlet or outlet pipes or lines.

To make operation safer, the flow control may be combined with another control which is placed at the entrance or sink inlet of the grinder housing. This companion control will permit water to flow into the grinder or not, as the operator prefers, but will prevent insertion of the operator's hand or other comparatively large objects into the casing while the grinder is operating. This second control may be eliminated, if desired.

Other objects and advantages, as well as details of that which I believe to be novel and my invention will be clear from the following description and the claims appended thereto, taken with the accompanying drawings in which is illustrated an exemplary form of waste disposal unit embodying the present invention. In the drawing, Fig. 1 is a partial section and side view of a waste disposal unit with controls according to

2

my invention; Fig. 2 is an elevation at right angles to Fig. 1 with certain parts removed; Fig. 3 is a plan view and partial section showing the "on" position of the sink stopper and associated flow control together with parts of the grinder interior; Fig. 4 is a bottom plan view of the sink stopper assembly alone in its "on" or grinding position; Fig. 5 is a diagram indicating the control mechanisms with their electrical connections and the motor which drives the grinder; and Fig. 6 is a partial section substantially on the line 6—6 of Fig. 1 showing the shape of certain parts.

As mentioned above, waste disposal units of the character involved in the present invention are customarily used in connection with a sink. Fig. 1 indicates the bottom of the sink at 10, with flanges 11 around the drain opening. The grinder housing 12 is located below the sink and it has a final discharge 13 to the trap or sewer. The grinder housing and its associated parts are joined to the sink discharge by means of a flanged cup-shaped fitting 14. A supporting ring 15 is threaded to this cup-shaped fitting and engages under a flange 16 on the top 17 of the grinder housing. A proper gasket or seal 18 is provided in order to decrease transmission of vibrations and to seal the assembly at this point. Bolts 19 extending between the housing and its top hold these parts together and their upper tips bear on a web 20 of annulus 21 which surrounds the cup-shaped fitting. After the threaded supporting ring and the housing top are assembled in proper relation with respect to each other, the threaded ring is fastened to the cup-shaped fitting and the bolts are tightened until the annulus bears against the underside of the flanges 11 around the sink discharge. A gasket 22 above the annulus is provided for sealing and cushioning of the assembly.

The grinder housing proper is connected to the assembly described immediately above by nuts 23 which are threaded onto the lower ends of bolts 19 after they are adjusted.

The top of the grinder housing contains a chamber 25 into which waste and water are fed for disposal. In the bottom of the grinder housing is located a fly wheel or rotary cutter 24 which is driven by shaft 25 from motor 26. Cutter blades 27 on the wheel cooperate with stationary cutters 28 on the inner walls of the housing so that when the fly wheel is rotating, the garbage or other waste is ground or cut up into tiny pieces, provided there is plenty of water present. Opposite the edges of the grinder fly

wheel are discharge openings or grooves 29 in the wall of the housing. When proper water is supplied, the comminuted waste will be washed through the openings to the discharge port or pipe 13 above mentioned.

In order to make sure that sufficient water is carried through the device, I provide a motor control which is located within or on the wall of the grinder housing alongside the chamber 85. This control operates to close the motor circuit only when sufficient water is flowing within the grinder housing. In order to keep this control separate from the waste or other material which has not yet been ground, I provide a water passage 30 in one side of the casing having an inlet 15 or entrance 31 and an outlet or exit 32, this passage having an outer gasketed cover plate 33 which is removably held in place, for instance, by screws 34. Outside of this cover plate is a housing or compartment 35 for the control switch 20 proper. This compartment may be provided with a cover 36 held in place by a screw 37.

Extending into the passage 30 from the switch compartment is an angular control lever 38 which is pivotally secured in the cover plate 33 through a stuffing box and bearing 39. On the inner end of this lever is a surface which may be in the form of a switch control disk 40. This disk will be in the stream of water flowing through the passage, for a purpose to be later described.

The outer end of the angular control lever is secured to a switch lever arm 41 within the switch compartment. This lever arm is provided with an adjustable tension spring 42 and variations in compression of this spring are obtained by a tension adjusting screw 43. By this means, the resistance of the disk to movement by water passing through the passage may be varied.

The lower end of the switch lever arm carries a switch adjusting screw 44 which bears against the plunger 45 of a switch 46. This switch is of the well-known character where a slight movement of the plunger will open the contacts 47 of the switch, the contacts being normally closed by a light spring 48 which is within the switch itself. The screw 44 provides for adjustment in the range of movement of the switch plunger stroke. By adjusting the tension spring and the screw 44, actuation of the switch may be obtained at any desirable predetermined flow of water through the passage.

Within the passage, and above the switch control disk, I provide a plate 49 which has an opening or nozzle 50. This will insure a proper concentration of water flowing through the passage 55 so that the water will be directed against the disk, to operate the angular lever on which the disk is mounted. Upon removal of the cover plate from the passage, the entire passage can be opened for inspection, cleaning, etc., and the nozzle plate may be removed by slipping it out of the grooves 51 in which it is seated in the passage.

It is desirable to keep the control passage clear from all materials except water. To accomplish this, a sloping face 52 is provided in the inlet, and this face carries a removable screen 53 which will prevent the introduction of solid particles of any substantial size. The sloping of this screen will help debris to be washed away. Alongside the lower end or exit of the passage a baffle 54 is provided in the wall of the grinder housing in order to prevent rotating waste from entering the water supply outlet 32. Rotation of the grinder flywheel is in the direction of the

arrow in Fig. 6. Note that the outlet and baffle are located above the shredding elements, at a level where centrifugal and erosive action are not severe.

Flow of water to the control passage described above is in turn controlled manually through a rotatable stopper 55. The position of this rotatable stopper 55 is governed by handle 56 to which a directional trough 57 is secured, for instance, by screws 58 threaded into the central post 59 of the handle. Collars 60 on the screws provide proper spacing of the directional trough from the under surface of the stopper. The trough has a discharge opening 61 which is turned with the handle so that water can be discharged through the stopper toward or away from the inlet 31 of passage 30.

Rotation of the stopper handle can also be used to provide for holding the water within the sink or for draining water from the sink without operation of the grinder, as well as draining water from the sink in a fashion to operate the grinder as desired. In order to hold water in the sink, a stopper plate or disk 62 is provided and this disk has a shouldered bottom 63 of generally circular form. However, in order to prevent rotation of this disk with respect to the cup-shaped fitting 14, the shouldered bottom is provided with unequal cutouts in the form of chords 64 and 65, and the opening 66 in the cup-shaped fitting is shaped to match and receive the shouldered bottom of the stopper plate. Because of the unequal extent of the two chords, the stopper plate will fit into the opening of the cup-shaped fitting in only one position. This will insure that the discharge from the trough will always be in the proper direction.

The handle is rotatably joined to the stopper plate but its movement is limited by the shape of the butterfly cutout 67 on the plate through which the central post 59 of the handle extends. This will be clear from Fig. 3. Further limitation of the handle movement with respect to the stopper plate is accomplished through the spring pressed balls 68 which are carried in the ends 69 of the handle. These balls ride in arcuate grooves or ball tracks 71 in the top surface of the stopper plate. Dimples or depressions 72 in these grooves establish three definite positions for the handle with respect to the plate.

In order to allow water to pass through the stopper plate, drain holes 73 are provided with a spacing of about 90° between each hole. These cooperate with a sealing plate member or spider 74 which is secured to the handle underneath the stopper plate. This spider has cutouts or openings 75 similar in shape and extend to the drain holes in the plate so that the openings in both pieces can be moved into registry for draining water from the sink or out of registry in order to seal the sink.

Angular lugs 76 and 77 on the sealing member cooperate to lock or unlock the stopper from the cup-shaped fitting, depending upon the relative position of the stopper handle with respect to the stopper plate. As shown in Fig. 4, these lugs overlie the chord cutout sections 64 and 65 of the stopper plate when the handle is in the "on" position of Fig. 3. Thus, these lugs will engage under the chord sections of the opening in the cup-shaped fitting and prevent removal of the stopper when the device is in this position although the drain openings are in registry. When the handle has been moved to the "seal" position, 75 these lugs will still partly overlie the chord sec-

tions and prevent removal of the stopper, but in this position the drain openings are closed. When the handle is moved still further to the "remove" position, the angular lugs are clear of the chord sections and the drain openings are open. Therefore, in this position, the stopper may be used as a drain if left in place or the stopper may be removed entirely from the sink.

The stopper assembly may also be used to obtain a control which aids in the safety of operation of the grinder when combined with the flow type of control already described. Stopper control is obtained by providing a sloping cam surface 78 on the angular lug 76 of the sealing member. This cam surface cooperates with a spring pressed crank arm 79 which is pivotally mounted in a wall of the casing through the stuffing box and bushing 81. The sloping cam surface has a maximum end 82 and a minimum end 83 which cooperate with a tip 84 on the crank arm to tilt the crank arm as the stopper handle is rotated from the "seal" to the "on" position. A spring pressed control switch 86 like switch 46 may be controlled by this crank arm or a simple toggle switch may be similarly controlled, with a spring provided to return the switch and the crank arm to their "off" positions when the tip of the arm is not depressed by the cam surface.

In operation, the stopper handle is first moved to the "remove" position and the stopper is lifted from the sink opening. When this is done (ignoring switch 86 for the moment) and assuming that no water is flowing in the sink, the switch 46 will be open and the grinder will not operate. The housewife or other user of the device can thereupon place the garbage or other waste into the chamber 85 above the grinding cutter with perfect safety. When it is desired to dispose of the waste, the stopper is inserted and the stopper handle is rotated to the "on" position. This action will open the drain holes. However, the grinder still will not operate unless sufficient water is provided. Therefore, when the water above the sink is turned on, it passes through the now open drain holes of the stopper and through the trough 57 from which it is directed into the passage 30. When the concentrated flow of water through the nozzle in this passage is of sufficient velocity, the force of the stream will depress the disk 40 and close the switch 46, thus starting the motor and operating the grinder.

The grinder operation will continue as long as there is sufficient flow of water to keep the disk depressed and as long as the stopper handle is in the "on" position. If, by some chance the water supply should fail, or the drain openings in the stopper should become clogged so that insufficient water passed through them, the disk would rise under the influence of the tension spring and break the motor circuit at switch 46, stopping the operation of the grinder.

On the other hand, if the handle is moved to the "seal" or "remove" position, operation of the grinder motor will be stopped by the opening of switch 46. Rotation of the handle away from the "on" position will turn the water directing trough so that water no longer discharges into the inlet of the flow control passage. This will open the flow control switch because of lack of water flow to the pressure responsive disk. Movement of the stopper to "seal" position will also open the flow control switch 46 by shutting off all water supplied to the casing.

If the switch 86 is used in combination with the flow control switch 46, it will assist in the safety of operation by opening the motor circuit whenever the stopper is removed, or is in either the "remove" or the "seal" position. The cam surfaces close the switch 86 only when the stopper handle is in the "on" position. However, it should be clear that the water flow controlled switch can be used alone to control the grinder motor, and without this stopper controlled switch, to make a less expensive construction.

It will be seen that the water confining passage, besides providing a convenient locus for the flow actuated drive control, will also insure that water entering the unit will be directed and discharged immediately above the grinder. Therefore, even if the waste chamber should be tightly packed with garbage, sufficient water will be enabled to pass downwardly to the grinder surfaces, enabling the grinder to operate and the ground waste to be flushed away.

Although I have shown and described but one example of the device according to my invention, it will be obvious to those skilled in the art that other embodiments, changes and modifications could be made without departing from my invention, and I, therefore, aim in the appended claims to cover all such embodiments, changes or modifications as fall within the true spirit and scope of my invention.

What I claim as new and desire to secure by Letters Patent of the United States is:

1. In a waste disposal unit, a housing having a fitting for connection to a sink drain to provide a water supply opening for said housing, said fitting including a rotatable member having a trough-like structure for diverting substantially all water flowing through said fitting toward the side of said housing, means for manually rotating said fitting, a waste grinding and water receiving compartment below said fitting, a waste grinder at the lower part of said compartment, a ground waste and water discharge beyond said grinder, a water flow conduit having an inlet at a side wall of said housing in alignment with the end of said trough and an outlet discharging tangentially into said compartment above the grinder, said conduit including inlet and outlet having a flow capacity exceeding the maximum requirement of said waste grinder, a first and a second electric switch in series in the motor circuit, means on said rotatable member for automatically closing the first switch upon rotation of said fitting to bring its trough into position to discharge into said conduit, and a sensing member in said conduit responsive to the minimum flow of water requirement of said waste grinder therethrough for closing said second switch.

2. In a waste disposal unit of the type having a water supply thereto, a waste grinding and water receiving chamber, a motor driven grinder at the bottom of the chamber, and a discharge beyond the grinder, that improvement which includes a water passage disposed externally of said chamber, said passage having a mouth communicating with said chamber near the top thereof and an outlet discharging tangentially into said chamber above the grinder, manually controllable means to direct water optionally from said supply means directly into said chamber or into said passage mouth, a switch in the energizing circuit of said grinder motor, and a pivotally mounted plate with actuation means for said switch disposed within said passage in the path

of water flow therethrough and responsive to a predetermined rate of flow therein to operate said switch to closed circuit position.

3. In a waste disposal unit of the type having a water supply thereto, a waste grinding and water receiving chamber, a motor operated grinder at the bottom of the chamber, and a ground waste and water discharge beyond the grinder, that improvement which includes a water confining passage in a side of the chamber, said passage having a flow capacity including inlet and outlet ends thereof exceeding the liquid requirement of said grinder with discharge from the outlet entering tangentially into said chamber in the direction of grinder rotation and above said grinder, a sloping inlet for said passage near the top of said chamber, means within said chamber for directing water from said water supply into said passage, a screen for said inlet, a grinder motor control switch, and a plate switch operator disposed in said passage near the discharge end thereof, said switch operator being responsive to the minimum flow of water requirement of said waste grinder through said passage and linked with said control switch for 25 operation of said motor substantially coincidentally with the introduction of said minimum flow of water above said grinder.

4. A garbage grinder unit of the type adapted to be connected to the drain of a sink, comprising a fitting for connection to the sink drain, a waste grinding and water chamber below the fitting, a grinder at the bottom of the chamber, a motor for driving the grinder, a water confining passage alongside the chamber having an 30 35

inlet immediately beneath said fitting and an outlet into said chamber above said grinder, said passage including inlet and outlet openings having a minimum cross-section which provides a flow capacity exceeding the maximum liquid requirements of said grinder, a motor control element in said passage operable to start said motor to drive said grinder upon the minimum flow of water requirement of said waste grinder through said passage, and a manually operable directional flow controller in said fitting, said flow controller having a water directing trough receiving substantially all the water flowing into said fitting and being optionally movable to any of three positions, in one of which the trough directs substantially all the water into the inlet of the water confining passage, in another position of which the trough directs water into said chamber away from said passage inlet, and in another of which said controller stops flow of water from the sink to the chamber.

JAMES H. POWERS.
